VISIBLE RECORD EQUIPMENT

Harry J. Hopkins, Chicago, Ill., assignor, by mesne assignments, to Acme Visible Records, Inc., Chicago, Ill., a corporation of Delaware

Application January 21, 1939, Serial No. 252,077

3 Claims. (Cl. 129—16.7)

This invention relates to improvements in visible record equipment, and refers specifically to a record card carrier of the type comprising a base or carrier card upon which a record card or cards may be removably mounted.

Visible record equipment of the type comprising a tray or frame upon which a plurality of carrier cards are hung, each carrier card serving as a support for one or more data carrying cards, have heretofore been used. However, no neat, simple and convenient means has heretofore been devised for removably supporting the data carrying cards upon the carrier cards.

My invention is particularly directed to a carrier card construction which is simple, neat, durable and which affords a convenient and effective support for a data carrying card or cards.

The objects and advantages of my invention will be apparent from the accompanying drawing and following detailed description.

In the drawing, Fig. 1 is a face view of a frame or tray upon which the carrier cards are mounted.

Fig. 2 is a sectional view through the carrier card and data bearing cards taken on the line 2—2 of Fig. 1.

Fig. 3 is an enlarged perspective view of one of the sleeves or envelopes for an upper corner of the carrier card.

Fig. 4 is an enlarged fragmentary face view, parts being broken away, of the carrier card and data bearing cards mounted thereon.

Fig. 5 is an enlarged fragmentary face view of the lower edge of one of the data bearing cards.

Fig. 6 is a sectional view taken on the line 6—6 of Fig. 4.

Fig. 7 is an enlarged perspective view of an envelope or sheath for the lower edge of the carried card.

Referring in detail to the drawing, 1 indicates a frame consisting of a web 2 having flanged edge portions 3 and 4 between which and the web the ends of hangers 5 are inserted and held. The frame may be provided with similar flanges (not shown) on the opposite side of the web 2 to permit cards and hangers to be mounted on both faces of the web. Cards 6 are hinged upon the hangers 5 by means of hinges 7 which are adapted to swing upon the hangers 5.

Each hanger may comprise a length of resilient metal consisting of a main body portion 8 having return-bent ends 9 extending inwardly for a limited portion of the length of the hanger. The ends of the return-bent portions may be offset as shown at 10 in Fig. 1, and are preferably bent inwardly toward the main body portion 8 so that

the ends of the return bends are parallel to the main body portion 8, as shown best at 11 in Fig. 1.

The hinge 7 is preferably formed of sheet metal and comprises essentially a sheet metal blank bent transversely intermediate its length 5 to provide an eyelet 12 which, in use, is engageable with the ends 11 of the hanger 5. In forming the eyelet 12 the faces of the blank on each side of the eyelet are disposed parallel to each other to form faces 13 and 14. The axis of the eyelet is preferably offset from the plane of the faces 13 and 14 so that when holding cards 6 in a frame the cards will lie flatly above the plane of the hangers 5. Tangs or lugs 15 are formed at the lower end of the face 13 and are adapted 15 to engage in pre-formed openings in the card 6.

As a feature of my invention an envelope or sleeve 16 is adapted to be mounted upon each of the upper corners of the card 6, said sleeve or envelope comprising essentially a blank of relatively tough sheet material such as Celluloid, relatively heavy "Cellophane", relatively light sheet metal or tough fibrous material. The blank 16 is folded along its axis of symmetry to form two oppositely disposed faces 17 and 18, the upper 20 edges of which are straight and are disposed substantially perpendicular to the line of fold 19. The lower edges of each of the faces are curved, as indicated at 20 in Fig. 3. Of course, in forming the envelopes the blanks will be folded oppositely for the right and left hand corners. 25

In mounting the sleeves or envelopes 16 upon the card corners, the upper edges 17 and 18 will be disposed in alignment with the upper edge of the card and the fold 19 will embrace the side 30 edge of the card. The sleeve or envelope may be provided with apertures 21 for the reception of the tangs 15 whereby said sleeves will be secured to the card by means of the hinges 7, or said sleeves may be riveted or stapled to the cards. 35

A sheath 22 is carried at the lower edge of the card 6, said sheath preferably comprising a transparent material such as Celluloid or the like. Of course, any of the materials specified in conjunction with the corner sleeves 16 may be used in 45 the construction of the sheath 22. The sheath 22 comprises an elongated blank which is folded longitudinally along the line 23, Fig. 7, to dispose faces 24 and 25 opposite each other. The upper edge of the face 25 is preferably reverse 50 folded, as shown at 26 in Fig. 7, to impart rigidity to the sheath. The face 24 is unfolded at its upper edge. The sheath 22 is mounted upon the lower edge of card 6 with the faces 24 and 25 embracing opposite faces of the card and the bot- 55

tom edge of the card disposed in fold 23. Staples 27 secure the ends of sheath 22 to card 6, said staples only passing through face 24 of the sheath. A staple 28 fastens the central portion 5 of face 24 to the central portion of card 6.

Although I have shown and described a sheath secured at the lower edge of the carrier card 6 by means of staples, it is to be understood that any type of similar sheath may be employed and 10 any suitable type of fastening means therefor is contemplated.

As has been hereinbefore described, the card 6 is intended to primarily function simply as a carrier card upon which data-bearing card 29 15 and 30 are removably mounted. The card 30 comprises a simple rectangular card approximating the width of the carrier card 6. To mount the card 30 on the card 6, the lower edge of card 30 is inserted between the face 25 of 20 sheath 22 and the carrier card, said edge being positioned adjacent the fold 23. The upper right and left-hand corners of the card 30 are inserted beneath the curved edge 20 of the sleeves 16, bringing the side edges of said corners adjacent 25 fold 19 and the top edges thereof adjacent tangs 15. In this manner card 30 may be mounted and retained upon one side of the carrier card, and when desired can be easily removed therefrom.

Card 29 is carried upon the opposite side of 30 card 6 in a similar manner. However, to insert the lower edge of card 29 between the face 24 of sheath 22 and the face of card 6, provision is made for staples 27 and 28. Accordingly the lower corners of card 29 are notched, as shown 35 at 31 and 32 in Fig. 5, and a central notch 33 is also provided. When card 29 is inserted behind the face 24 of sheath 22, the notches 31, 33 and 32 register with staples 27, 28 and 27 respectively, and permit the lower edge of card 29 to be disposed adjacent fold 23. The upper corners of 40 card 29 are positioned beneath sleeves 16 in a manner similar to the positioning of the respective corners of card 30.

It can readily be seen that the sleeves 16 and 45 sheath 22, in addition to functioning as retaining means for cards 29 and 30, also function as

reinforcing or protective agents for the most vulnerable portions of the card 6, that is, the corners and lower exposed edge. Further, the sleeve 16, when hinges 7 are mounted, as described, prevent the tangs 15 from tearing the carrier card. 5

I claim as my invention:

1. A sleeve for receiving an upper corner of a data-bearing card, in combination with a relatively flat carrier card having defining edges, and hinges secured to said carrier card, the said sleeve 10 comprising sheet material disposed parallel to one face of the carrier card adjacent an upper corner thereof and retained by one of said hinges thereupon to form an individual pocket adjacent said corner and to aid in holding said data-bearing card and said carrier card in plane-parallel relationship. 15

2. A sleeve for receiving an upper corner of a data-bearing card, in combination with a relatively flat carrier card having defining edges, 20 and hinges secured to said carrier card, the said sleeve comprising folded sheet material disposed parallel to and overlying the faces of the carrier card adjacent an upper corner thereof and underlying and retained by one of said hinges thereupon to form an individual pocket adjacent said corner and to aid in holding said data-bearing card and said carrier card in plane-parallel relationship. 25

3. A sleeve for receiving an upper corner of a data-bearing card, in combination with a relatively flat carrier card having defining edges, and hinges secured to said carrier card by means of lugs extending into pre-formed openings in the card, the said sleeve comprising a blank of sheet 30 material folded along its axis of symmetry to form oppositely disposed faces disposed parallel to and overlying the faces of the carrier card adjacent an upper corner thereof and provided with openings registering with the said openings in 40 the carrier card and retained thereon by one of said hinges and the lugs thereof to form an individual pocket adjacent said corner and to aid in holding said data-bearing card and said carrier card in plane-parallel relationship. 45

HARRY J. HOPKINS.
